UNITED STATES PATENT OFFICE

PERCY M. FORSTER, OF BERKELEY, CALIFORNIA

BLOWTORCH

Application filed December 10, 1929. Serial No. 413,064.

This invention relates to blow torches of the type disclosed in my copending application entitled "Torch", filed November 26, 1929, Ser. No. 409,837, and has for its principal object the provision of a simple and efficient blow torch utilizing natural gas as a fuel.

In carrying the invention into practice the air and natural gas are first admitted to a mixing chamber in which baffles are arranged so that the gas and air will be thoroughly mixed before being ejected at the burner tip. The burner tip is so constructed that streams of the gaseous mixture are caused to converge at a point just beyond the burner tip so that sharp intense flame will be created. In order to obtain a flame of greater heat than that provided by just natural gas and air I have provided means for delivering additional oxygen and compressed air to the burner tip.

One form which the invention may assume is exemplified in the following description and illustrated by way of example in the accompanying drawings, in which:

Fig. 1 is a side elevation of a torch embodying the preferred form of my invention.

Fig. 2 is a central section through the same.

Referring more particularly to the accompanying drawings, 10 indicates a torch or burner utilizing natural gas as a fuel. This torch or burner comprises a casing 11 which encloses a mixing chamber 12. The ends of the casing 11 are closed. Connected with one end of the casing is an inlet pipe 14 fitted with a T 15 to which is connected a compressed air pipe 16 and a pipe 17 for delivering natural gas to the pipe 14. The pipes 16 and 17 are each fitted with a valve so that the quantity of compressed air and natural gas delivered to the pipe 14 may be regulated. At the opposite end of the casing 11 is a delivery pipe 18, the outer end of which terminates in a burner tip 19.

The interior of the casing 11 is so baffled that the natural gas and air admitted thereto through the pipe 14 will be thoroughly

mixed before it is delivered to the pipe 18 and discharged at the burner tip 19.

Reference being had to the drawings it will be noticed that just within the end of the casing 11 into which the pipe 14 projects is a curved baffle plate 20, one end of which is not in contact with the casing 11 so that the air and gas entering the chamber will be caused to swirl and pass around the free end of the baffle 20.

At spaced intervals beyond the baffle 20 are perforated plates 21, two of which are provided with a series of perforations while the other is provided with a single perforation. These perforated plates also assist in causing the gas and air to thoroughly mix. As the gas and air pass through the last baffle plate 21 they engage a cupped baffle plate 22 secured on the inner end of the pipe 18. This engagement causes the gas and air to swirl as they must pass around the plate 22 before entering the ports 23 in the pipe 18. The series of baffle plates just mentioned causes the gas and air to thoroughly mix while passing through the chamber 12.

It is desired to point out that the lack of oxygen in natural gas prevents it from igniting until it has mixed with a sufficient quantity of oxygen. Thus, if the natural gas and air were ejected separately directly at the nozzle the flame would be spaced from the nozzle and result in an inoperative burner. I overcome this, of course, by first thoroughly mixing the air and gas before discharging it under pressure from the nozzle.

Surrounding the burner tip 19 is a cylindrical shield 24 which is of a diameter somewhat larger than the burner tip 19. The space between the inner end of the shield 24 and the pipe 18 is closed as at 25 while the outer end of the shield is open.

Arranged exteriorly about the shield 24 is a series of small tubes 26 which are connected at their inner ends 27 with the pipe 18 while their outer ends are connected with the shield 24 just beyond the tip 19. The ends of the feed tubes 26 which communicate with the outer end of the shield 24

are arranged angularly with respect to the axis of the shield 24 so that the small fine streams of gas discharged from the tubes 26 will converge toward the center of the shield and thus make a very fine sharp flame when the torch is in operation.

In order to create a hotter flame when desired I have provided means for delivering additional air under pressure or oxygen to the burner tip. This means comprises a pair of fine tubes 30 and 31 which extend along the casing 11 and thence centrally through the pipe 18 to a point at the burner tip 19. These tubes are both controlled by valves 32. One of the tubes is connected to a source of oxygen while the other is connected with a source of compressed air.

It will be noted that as the oxygen delivery tube extends to the tip it does not mix with the gas at any time until the gas leaves the tip, thus preventing any danger of explosion.

I also desire to point out that the streams of gas and air ejected from the small tubes 26 are directed to a point where they will not be blown out when air or oxygen is delivered from the pipes 30 and 31.

In operation of the device compressed air and natural gas is admitted to the mixing chamber 12 and due to the baffle plates 20 and 21 will be thoroughly mixed before delivery to the pipe 18. As the gaseous mixture thus formed discharges from the tip 19 it is ignited. The suction created will draw the gaseous mixture through the tubes 26 and cause a plurality of fine flames to converge toward the center of the tip creating a sharp and intense flame which, of course, is very desirable.

40 To make the flame hotter so that it may be used for burning and welding, additional compressed air or oxygen may be delivered to the burner tip through the pipes 30 and 31. I have found in actual practice that a burner constructed in accordance with the invention just disclosed is very efficient for use in connection with natural gas.

While I have shown the preferred form of my invention, it is to be understood that 50 various changes may be made in its construction by those skilled in the art without departing from the spirit of the invention as defined in the appended claims.

Having thus described my invention, what 55 I claim and desire to secure by Letters Patent is:

1. A burner nozzle comprising a cylindrical burner tip, a cylindrical shield arranged concentrically thereabout, and a plurality of separate fuel ducts surrounding the shield for directing flames converging toward the center of the tip at a point just beyond the same.

2. A burner nozzle comprising a cylindrical tip, a cylindrical shield of a larger di-

ameter than the tip arranged concentrically thereabout, a plurality of small tubes connected with the shield for directing a plurality of converging flames toward the center of the shield at a point just beyond the tip.

3. A torch comprising a casing to which gas and air is delivered, said casing being fitted interiorly with baffle plates for mixing the gas and air, a pipe extending 75 from the casing and terminating in a cylindrical tip, a shield surrounding the tip, a plurality of tubes connected at one end with said pipe and the other end with said shield, said tubes at the point where they join the shield being angularly disposed whereby a plurality of streams of gas and air will be caused to converge toward the center of the shield at a point just beyond the tip, and separate oxygen and compressed air delivery tubes extending centrally through the pipe and terminating at the tip.
